UNITED STATES PATENT OFFICE.

JOSEPH KARUS, OF NEW YORK, N. Y.

CAP.

Application filed January 20, 1922. Serial No. 530,529.

To all whom it may concern:

Be it known that I, JOSEPH KARUS, a citizen of Jugo-Slavia, residing at New York city, county of Bronx, borough of Bronx, 5 and State of New York, have invented new and useful Improvements in Caps, of which the following is a full, clear, and exact specification.

My invention relates to caps and refers 10 particularly to storm caps.

One of the objects of my invention is a cap capable of being placed in folded and unfolded positions, in order to accommodate it to the weather and to increase its protective attributes when desired.

Another object of my invention is a cap of such construction as will allow of its being changed from one position into another without danger of so disrupting its 20 general character as to render it ineffective and objectionable.

These and other objects of my invention will be evident upon a consideration of my drawings and specification.

25 In the particular form of the device of my invention, as shown in the accompanying drawings, similar parts are designated by similar numerals.

Figure 1 is a perspective view of one form 30 of the device of my invention shown in folded position.

Figure 2 is a perspective view of Figure 1 with the visor in unfolded position.

Figure 3 is a perspective view of Figure 1 35 in an unfolded position.

Figure 4 is a side plan view of Figure 1.

The particular form of the device of my invention, shown in the accompanying drawings, comprises a head-piece, which may be 40 composed of two similar portions 10 and 11 fastened together along the seam 12.

A neck-piece 13 is fastened to the head-piece along the seam 14. The neck-piece 13 is angularly extended into the throat-pieces 45 15 and 16.

Each throat-piece 15 and 16 is maintained in the positions shown in Figures 1, 2, and 3 by means of the fastener 17 carried by the head-piece which is capable of attachment 50 to a fastener 18 carried by the throat-piece 15. The reverse side of one of the throat-pieces 15 carries a fastener 19 which is capable of attachment to the fastener 18 carried by the other throat-piece, thus allowing the throat-pieces to be attached to 55 each other, as shown in Figure 3.

The neck-piece 13 is further attached to the head-piece 10 and 11 along the arc-shaped seam 20.

A visor 21 is fastened to the head-piece 10 60 and 11 along the seam 22 and along the arc-shaped seam 23.

The seams 14 and 22 are in a practically straight line with respect to each other.

Having thus described the device, as shown 65 in the accompanying drawings, I will describe its various uses and applications as follows:—

Figures 1 and 4 show the cap as worn in ordinary weather, the neck, throat and face 70 being unprotected.

When it is desired to protect the face, the visor 21 is pulled downwardly along the seam 23. The arc-shaped formation of this seam causes the visor 21 to assume and maintain 75 an outwardly and downwardly position, at the same time having a curved position around the upper portion of the face. This particular formation and position of the visor 21, caused by the arc-shaped seam 23, 80 gives it a much greater stability and efficiency than would be the case if it were unfolded along the seam 22.

When it is desired to provide the maximum of protection, the neck-pieces 15 and 85 16 are unfastened from the fasteners 17, 17 and the neck-piece 13 folded downwardly along the arc-shaped seam 20 and the throat-pieces 15 and 16 are brought forwardly under the chin of the wearer and fastened together by the fasteners 18 and 19. The device has then assumed the position shown in Figure 3.

It will be noted that the arc-shaped seam 20 maintains the neck-piece 13 in a downwardly 95 and outwardly extended position, thus allowing it to fit snugly upon the lower portion of the neck and upon the shoulders of the wearer.

The neck-piece 13 and the throat-pieces 15 100 and 16 may be worn in a downwardly extended position, while the visor 21 is retained in its upward position.

A very valuable and useful feature of the arc-shaped seams 20 and 23 is shown when 105 the device is converted from its unfolded condition, as shown in Figure 3, into its folded condition, as shown in Figures 1 and 4.

To accomplish this, the visor 21 and the 110 neck-piece 13 are pulled upwardly as far as they will go, this upward movement being

stopped by the seams 20 and 23, thus allowing the seams 14 and 22 to remain in a straight line with respect to each other and maintaining the cap in proper position. If 5 it were not for these arc-shaped seams, there would be a liability of pulling the visor and neck-piece too far, thus causing the seams 14 and 22 to be also pulled upwardly, resulting in an upwardly formed, uncomfortable 10 and inefficient head covering.

While I have shown the device as knitted, it is evident that it may be produced from any other suitable material.

It will thus be seen that my invention 15 presents a new, novel and useful device, capable of a number of applications and which is simple in operation and effective in results.

I do not limit myself to the particular size, 20 shape, number or arrangement of parts, as shown, this particular form of my device

being given simply as a means of describing my invention.

What I claim is:—

In a cap, in combination, a head-piece, a 25 neck-piece attached to the head-piece and extending around a portion thereof, an arc-shaped seam above the bottom line of the head-piece connecting the neck-piece and the head-piece, upwardly and forwardly extended portions of the neck-piece forming throat-pieces, means for attaching the throat-pieces to the head-piece, the neck piece being capable of being folded downwardly around the neck of a wearer and the throat-piece being 30 capable of being folded downwardly around the throat of a wearer and means for fastening the two throat-pieces to each other. 35

Signed at New York city, in the county of New York and State of New York, this 18th day of January, 1922.

JOSEPH KARUS.
